TRANSMISSION SYSTEM FOR STATISTICAL DATA

James W. Bryce, Glen Ridge, N. J., assignor to
International Business Machines Corporation,
New York, N. Y., a corporation of New York

Application October 19, 1938, Serial No. 235,819

10 Claims. (Cl. 178—4)

This invention relates to transmission systems for statistical data and, more particularly, to those systems of the so-called "check back" type wherein data received and recorded at a distant station is analyzed and retransmitted to the initial station for purposes of verification. One form of such a check-back system is disclosed herein, another form being shown in my copending application Serial No. 235,820 and still another form being shown in my copending application Serial No. 235,821.

It is the general object of the instant invention to provide a unique system for transmitting statistical data including novel means for effecting the verification of the data transmitted.

More particularly, it is the object of the invention to print and transmit statistical data to effect printing and punching of said data at some distant point, novel means being then provided for the punched data to be retransmitted to the original point for visual verification.

It is within the contemplation of the invention to provide a system for transmitting data in which transmission is effected at one speed and re-transmission is effected at the same or any other desired speed for the purpose of verifying said data, and in which an indication is made to appear at the receiving station when the retransmitted data has been correctly verified.

It is also contemplated to provide automatic timing means to indicate when the control elements of each station of the system are in need of adjustment, and accordingly to provide means to send out a special repeat signal from each station to bring the other station automatically into adjustment.

Another object of the invention is to provide a novel storing mechanism set up from data punched in a record card and utilized in retransmitting said data for verification purposes.

Another object is the provision of means whereby transmitting from the card data storing mechanism in any column is prevented until all mechanisms for effecting such transmission are definitely positioned with relation to that column.

Still another object is to provide a novel system for transmitting data in which multiple impulses representing data are sent out from the transmitting station and cause energization of a chain of value manifesting relays at the receiving station according to the number of impulses received during a predetermined time interval, said relays then controlling the printing and punching means for recording said data at the receiver.

According to the present invention, a contact control key at a station "A" is operated to send out a series of impulses which cause a record card to be fed into a punching position at a station 5 "B," located at a distant point from station "A." Then, upon depression of a character key, printing of the corresponding characters is effected at station "A," and at the same time a series of impulses are sent to station "B" to cause the energization of a chain of relays there to a pre-determined extent dependent upon the character transmitted. These relays control the operation of means for printing and punching the character at station "B." Immediately following the 10 punching operation, the character perforation is analyzed and sent to a relay storing mechanism. Other characters are transmitted in a similar manner, and the perforations in the record card are analyzed and stored until the card is completely punched, at which time the storing mechanism effects transmission of the punched data from station "B" back to station "A." At station "A," this data is received and printed to provide a visual check against the previously printed data at station "A." If there is an agreement, a new record card feed and carriage return is initiated. If there is no engagement, an adjusting key at station "A" is depressed to adjust station "B" and also visually to indicate at that station the failure of the re-transmitted data to verify. At station "B" the newly punched record card is removed and, after station "A" has adjusted "B," station "B" adjusts "A." Operations are then resumed as before. The importance of having an accurate check-back on the transmitted data as described above, especially in statistical work which deals primarily with numerical values, is well realized by those familiar with the art.

In the drawings:

40 Figs. 1 and 1a are representative circuit diagrams of the transmitter and receiver respectively at station "A."

Fig. 1b is a timing chart for the circuit diagram shown in Fig. 1.

45 Figs. 2 and 2a are representative circuit diagrams of the receiver and transmitter respectively at station "B."

Fig. 2b is a timing chart of the circuit diagram shown in Fig. 2a.

50 Fig. 3 is a plan view of a portion of the transmitted key board.

Fig. 4 is a sectional view taken at 4—4 of Fig 3.

Fig. 5 is a sectional view taken at 5—5 of Fig. 3 showing a transmitting key and the various operating mechanism associated therewith.

Fig. 6 is a view of the dash pot control mechanism which is applied to certain relay contacts in the various circuits of the system.

Fig. 6a is a detail plan view of the mechanism associated with the dash pot.

Fig. 7 is a detail elevation view showing the card analyzing brushes and a portion of the punching mechanism.

A preferred embodiment of the invention will now be described with reference to the accompanying drawings.

CHARACTER KEY CONTROL

At station "A" a special keyboard is provided as shown in Figs. 3, 4 and 5. Seven keys are shown as representative, three of them being allotted to numerical characters and the remaining four being provided for various control operations such as space control, card feed, verifying, and adjusting. If more than three different numerals are to be transmitted more numeral keys are added, but the four control keys are sufficient regardless of an increase in the numeral keys. Depression of any of the keys causes the operation of a special set of contacts associated therewith so as to initiate a corresponding impulse or series of impulses. If a numeral key is depressed, it also causes printing of the numeral by energizing a print solenoid associated therewith, all of which will be described in detail hereinafter. The mechanism illustrated in Fig. 5 in association with the adjust key 17 is similar to that for the other keys. It is seen that the depression of key 17 causes an insulated conducting portion 17a to bridge the contact springs 17b. A notched projection 17c at the same time cams latch bar 19 to the right and then allows it to return to the left again under spring action so that the left extremity of bar 19 is positioned above the latch point on projection 17c to hold the key down. Then at a later time, as will be described later, solenoid 18 becomes energized momentarily to move the latch bar 19 to the right away from projection 17c, thus releasing the key 17 and allowing it to raise to its normal position under the urging of its return spring 17d. It will be noted that only one key may be depressed at a time due to the presence of locks 8 (Fig. 4). When a key is down it maintains the locks adjacent thereto spread apart so that the combined clearance of the locks 8 is taken up and no other key may be moved down between them. This structure is elementary and similar to that used in key-operated punches to prevent the operation of more than one key at a time so that no further description is believed necessary.

TRANSMITTING COMMUTATOR

A transmitting commutator 20 (Fig. 1) and a rotatable arm 21 are also located at station "A," arm 21 being maintained continuously rotating in a clockwise manner at uniform speed by any suitable means such as an electric motor (not shown). The speed at which this arm is to rotate is determined by two factors; namely, the desired speed of transmission of the impulse and the speed of functioning of the receiver mechanism at station "B." As arm 21 traverses the various transmitting segments of the commutator 20, a plurality of circuits are successively closed depending upon which of the keys 11 to 17 was operated to effect the transmission of a predetermined number of impulses from the transmitting device 43. The circuits will be described in detail later.

RELAYS AND SOLENOIDS

The mechanism actuated at the receiver of station "B" by the incoming impulses comprises a chain system of multiple contact relays R1 to R7 (Fig. 2) which control the selective energization of a plurality of print solenoids, such as the one designated 62 for example. Solenoid 62, upon becoming energized, pulls its armature 62a and the key lever connected thereto down so as to operate a printing mechanism which is diagrammatically represented by a platen 57, a hammer 57a, and suitable linkage 57b connected between the hammer and the key lever. Motion transmitted through the linkage 57b causes the hammer to be moved toward the left to strike the platen. The leftward movement of the hammer closes a contact 62b to energize a punch solenoid 72 by a circuit to be described later. Punching mechanism of any convenient type such as shown in the U. S. Patent No. 1,772,186 to F. L. Lee et al., for example, may be employed. Printing and punching under solenoid control are old in the art, and therefore the representation of the printing and punching means illustrated in Fig. 2 and Fig. 7 respectively are believed sufficient.

A CARD ANALYZING MECHANISM

An analyzing mechanism is located just beyond the punch die so that just after a perforation is made in a column of the card and the card has escaped to the next column, the perforation may be analyzed. The analyzing means comprises contact balls 22 (Fig. 7) mounted in an insulating support and spring-pressed towards the card C. Above the card there is a contact block 23. It is understood that, when a perforation passes over one of the balls 22, that ball is urged upwardly by its spring to establish contact with the contact block 23. Referring to Fig. 2a, it is seen that cooperating with the analyzing mechanism is a storing device comprised of a plurality of relays, such as relays 77 to 80, for each column of the card. A selecting device comprising two emitter strips 81 and 82 and a pair of brushes 83 and 84 respectively is provided to manifest the column on the card being analyzed and to choose the corresponding section of the storing mechanism in which the digit value represented by the perforation in that column is to be stored. The brushes 83 and 84 are mounted on a portion of the card carriage in the manner shown in Fig. 5 of the U. S. patent to Daly No. 2,045,437 so that as the card escapes from column to column while being punched, the brushes are advanced from segments 85a and 85 to segments 86a and 86, etc.

READ OUT

A read-out device for the storing mechanism at station "B" is provided and comprises a commutator 24 and an arm 25. This device becomes operable after a card has been fully punched to read out the data from the storing mechanism and, in cooperation with a transmitter 125, to send impulses representing that data back to station "A." A chain system of relays forms a receiving means at station "A" similar to that already described for the station "B" receiver. Arm 25 is rotated in a uniform manner by means similar to that for arm 21 but not necessarily at the same speed.

SYNCHRONIZING MEANS

Although the commutators at stations "A" and "B" do not run in synchronism, there is a cer-

tain time controlled relationship between the receiving portion of each of these stations and the transmitting portion of the other. This comprises a control relay 55 at the receiver of each station having dash pot mechanism generally designated 54 (Fig. 6) associated therewith to control the time of operation of a plurality of sets of contacts including those designated 55b, 55c, 55d, and 55e. Relay coil 55, upon becoming energized attracts the armature 5 so that a piston 5a attached to the right extremity of the armature is moved down forcing air out through an opening 7 in the dash pot 54. It is seen that the speed of closing of contacts 55b, 55c, 55d, and 55e are dependent upon the size of the opening 7 which is adjustable in a manner to be explained presently. When the relay coil 55 is deenergized, the outside air rushes in through the opening 8 and the armature is allowed to restore quickly under spring action and return the above contacts to their normal position.

The size of the opening 7 is manually adjustable by turning knob 6 which is fixed to a threaded shaft 6. Automatic means for rotating the shaft 6 in either direction is also provided so as to speed up or slow down the closing of the contacts under control of the dash pot mechanism. A train of gears, generally designated 4, connects the shaft 6 for operation by a differential device 66 actuated by a pair of pawls 91, 92 and ratchets 66a, 66b. The shaft 6 forms a frictional mounting for one of the gears of the above train. The ratchets may be locked or released according to the position of a pair of cooperating detents 2 and 3. The detents are normally in the position shown in the drawings and are mounted on a common shaft 1. A solenoid X controls the engagement and disengagement of the detents. When detent 2 is disengaged from ratchet 66a, detent 3 is engaged in ratchet 66b. A magnet 135, when energized, causes the pawl 91 to feed ratchet 66b clockwise one tooth. A magnet 136 cooperates with pawl 92 to feed ratchet 66a counterclockwise one tooth. The manner in which these magnets are energized will be better understood later from the description of the circuits of the system. It is sufficient for the present to state that the stepping of ratchet 66b in a clockwise direction causes the threaded shaft 6 to back up by motion transmitted thereto through the gear train 4 and allow an increase in the size of opening 7. On the other hand, the counterclockwise movement of ratchet 66a causes motion to be transmitted through the gear train 4 to turn shaft 6 clockwise thereby decreasing the size of the opening 7. Thus, ratchet 66b is operated in the direction indicated by the arrow to speed up dash pot action and ratchet 66a is operated to slow down this action. The solenoid X is located in series with magnet 136 and is energized when the latter is energized so as to release the ratchet 66a. Ratchet 66b is normally free of detent 3 so that solenoid X need not be operated upon the operation of magnet 135. The purpose of the dash pot control mechanism and the automatic adjustment therefor will be explained in connection with the explanation of the circuits and operation of the system which now follows.

GENERAL OPERATION

At the start it is assumed that the printing means comprising two typewriters at station "A" and one at station "B" have paper inserted there-

in and that the punch at station "B" has a pack of fresh record cards in its hopper, and that the two stations are in adjustment which is described later. It is first necessary to feed a card from the hopper between the die and stripper of the punch to a punching position. This is accomplished by transmission of a predetermined number of impulses from station "A" to station "B." These impulses cause the energization of a selected control magnet of the chain relay system already described which in turn causes the punch clutch magnet to be energized in a manner to be described presently. A key 15 (Fig. 1), referred to as the card feed key, is depressed (see Fig. 5 and Fig. 1) to initiate the above operation.

Card feeding

The depression of the card feed key 15 causes conducting portion 15a to bridge contact springs 15b and complete a circuit to connect relay coil 35 directly across the line. Relay 29 also becomes energized by a circuit from right hand side of the line 27, wire 28, contacts 35a now closed, relay coil 29, to left hand side of the line 26. Relay 29, when energized, closes its contacts 29a which in turn complete a circuit to energize clutch magnet 40 as follows: right hand side of the line 27, contacts 29a now closed, clutch magnet 40, to left hand side of the line 26. The energization of magnet 40 causes the cam associated with contacts CC-3 to be clutched in for rotation with the same shaft which carries arm 21. Cam CC-3 therefore now rotates in synchronism with the arm 21 from the "D" position onward. Near the end of the next cycle, the cam causes the closure of its contacts CC-3 for a purpose which will be explained later. It might be well to mention here that the depression of any of the keys 11 to 17 causes the clutching in of the CC-3 cam to the commutator shaft and the energization of relay coil 29.

The energization of relay 35 upon depression of the card feed key 15 causes the closing of contacts 35a and c-g. A circuit is completed through contacts 35a at the time arm 21 contacts segment 20a of the commutator 20 in the following manner: from line 27, wire 28 to contacts 35a now closed, relay coil 30, contacts 38b, commutator segment 20a, arm 21, to line 26. Relay coil 30, upon becoming energized by the above circuit, closes its contacts 38a to cause the energization of relay coil 38 from line 27, contacts 38a, relay coil 38, to line 26. The holding circuit for relay 38 is through contacts 38a now closed and cam contacts CC-4. As previously mentioned, the CC cams are driven at the same speed as arm 21, and when the arm 21 is at line D of commutator 20, the CC cams are in the well-known "D" position as illustrated in the timing diagram (Fig. 1b). Relay 38 is provided with contacts 38b which are located in series with the transmitter 43 and are normally open. Thus, it is seen that transmission may be effected only when the energization of relay coils 30 and 38 has occurred previous to the passage of arm 21 over the various transmitting segments of the commutator 20.

Transmitting circuit

With relay 38 energized, a series of impulses may now be transmitted. The transmitting circuit is from line 27 through resistance 41, contacts 38b now closed, wire 42, contacts 35g now closed, relay coil 45, segment spot 20b, arm 21, to line 26. The flow of current through resist-

ance 41 causes a potential drop across it which is impressed upon the input of the transmitter 43 to cause an impulse to be sent out from station "A" to station "B." Relay 45, upon being energized by the previously traced circuit, closes its contacts 45a to energize relay coil 44 from line 27, through relay contacts 45a, through relay coil 44, to line 26. Relay coil 44 is then held energized through its contacts 44a and cam contacts CC-2 until the end of the transmitting period (see timing diagram, Fig. 1b). As the rotating arm 21 successively contacts the segment spots 20c, 20d, 20e, and 20f, additional impulses are sent out from transmitter 43. In this case, that is, where key 15 is depressed, the contacts 35c through 35g cause transmission of impulses, five in number. Assuming the key 15 has been released by the operator, it is still held in a down position by latch 19 in a manner already described for key 17.

Interlocking circuits

Following the transmitting portion of the cycle, a circuit is completed to energize relay coil 39 by means of the arm 21 from line 26, through arm 21, through segment spot 20n, through contacts 44b now closed, relay coil 39, to the other side of the line 27. Relay coil 39 is held energized through its contacts 39a and relay contacts 29b now closed. The energization of relay coil 39 by the above circuit opens its contacts 39b and prevents energization of the relay coil 30 should the key 15 remain depressed for another machine cycle. This effectively prevents transmission of a repeated series of impulses for the same depression of the key. Key 15 is released near the end of the cycle when cam contacts CC-3 close to energize relay 18, which shifts latch 19 (Fig. 5) to permit key 15 to move upward under spring action in the same manner as illustrated for key 17. If the operator, however, has not yet released key 15, the shifting of latch 19 has no effect and magnet 40 remains energized due to continued closure of relay contacts 29a. Once the operator removes pressure from the key, however, the next shifting of latch 19 will release key 15 thereby deenergizing relay coil 29 and consequently relay coil 39. Relay contacts 39b then are allowed to close once more and, upon the next key depression, a new series of impulses may be transmitted.

Receiving mechanism

The five impulses transmitted in the manner just described are received at station "B" and effect a card feed there as follows: Upon reception of each impulse at station "B" (Fig. 2) the receiver 50 is actuated accordingly and causes the energization of relay coil 52 for each impulse. Coil 52 closes its contacts 52a upon each energization. The first impulse completes a circuit from line 46, relay contacts 52a now closed, through center and upper relay contacts 51a, R1b, R2b, etc., through R1b, wire 49, relay coil 51, and back to the other side of the line 47. Relay coil 51 then shifts its "make before break contacts" 51a, that is, the center and upper contacts make before the center and upper break. Coil 51 thus remains energized for the duration of the first impulse through relay coil 52. Contacts 51b close and cause the energization of relay coil R1 from the left-hand side of line 46, through contacts 53a, contacts 51b, contacts R1a, relay coil R1, to line 47. Relay coil R1 is main-

tained energized through contacts R2d, the holding circuit being from line 47, relay coil R1, contacts R1a, relay contacts R2d, contacts 53a, to line 46. The contacts R1a are also of the "make before break" type. Relay contacts 51c also close to cause the energization of relay coils 55 and 55' by completing a circuit from line 47, relay coils 55 and 55' in parallel, contacts 51c now closed, to line 46. The holding circuit for these coils is through contacts 55'a, 60, 61, 53b, and 63a.

A plurality of contacts are operated under the control of relay coils 55 and 55'. Those operated by coil 55, including contacts 55b, 55c, 55d, and 55e, are provided with dash pot control mechanism as already described. Contacts 55'a and 55', which are operated by relay coil 55', are not dash pot controlled. The purpose of the dash pot is to prevent any one of the chain relays from being energized to effect control until the completion of the time during which all possible signal impulses have entered the chain relay group. Accordingly, the adjustment of the dash pot is such that contacts 55b do not close until the arm 21 at station "A" has contacted the segment spot 20m. The adjusting circuits will be explained later.

The next impulse which enters the chain relay group causes the energization of relay coil R2 by the following circuit: from line 46, relay contacts 52a, relay contacts 51a in the position shown, relay contacts R1b in a transferred position, relay contacts R2a, relay coil R2 in the position shown, to line 47. Relay coil R2, upon being energized, shifts its a, b, c and d contacts. The shifting of the R2d contacts, which are of "make before break" type previously described, transfers the holding circuit for relay R1 back through contacts 52a. Therefore, upon opening of these contacts, relay R1 is deenergized. Relay R2 is held energized through contacts R2a and R3d. In a similar manner each successive impulse entering the chain causes an energization of a new relay and deenergization of the previous one. When the five impulses representative of a card feed are all received, relay R5 is energized to manifest this fact. Shortly thereafter relay contacts 55b close and a circuit is completed as follows: from line 46, relay contacts 55b, switch 56 now closed, contacts R1c, R2c, R3c, and R4c in the position shown, contacts R5c now in a shifted position, solenoid 67, to line 47. This circuit energizes solenoid 67 causing it to pull down its plunger 67a and to close its contacts 67b. The closing of contacts 67b completes a circuit to energize relay coil 68 as follows: from line 46, relay coil 68, contacts 67b, to line 47. The depression of plunger 67a also closes contacts 67c causing relay coil 53 to become energized by a circuit from line 47, contacts 67c, relay coil 53, to line 46. Relay coil 53, upon energization, opens its contacts 53a to deenergize relay R5, and also opens its contacts 53b to deenergize relay coil 55'. With the energization of relay coil 68, contacts 68a close to complete a circuit from line 46, through contacts 68a, through the punch clutch magnet 70 and back to the right-hand side of line 47. Energization of punch clutch magnet 70 shifts contacts 69 to energize the punch motor 65 by completing a circuit thereto from the left-hand side of line 46, through contacts 69, through motor 65, and back to line 47. The punch motor 65 then operates to effect the feeding of a new record card to the punching position.

Digit impulse transmission

Station "B" is now ready to receive the impulses representative of statistical data from station "A." One of the digit keys at station "A," for example, key 12 (Fig. 1), is now depressed and closes its associated contacts 12b in a previously described manner to effect the energization of the relay coil 32. The closure of contacts 32b then completes a circuit from line 26, through contacts 32b now closed, through typewriter solenoid S2 and back to the right-hand side of line 304. Energization of solenoid S2 causes printing of the numeral "2" at station "A." Closure of contacts 32a causes a pickup of relay 36 and also relay 38 as previously described so as to prepare the transmitting circuit. Closure of contacts 32c and 32d then permits transmission of two impulses from station "A" to station "B," the transmission of these impulses being effected in the same way as for the card feed impulses.

Digit impulse reception

At station "B," upon reception of the two impulses, relay coil R2 becomes energized and, at the time dash pot contacts 55b close, a circuit is completed from the left-hand side of the line 46, through contacts 55b, receiving switch 56 now closed, through contacts R1c in position shown, through contacts R2c in a transferred position, through solenoid 62, to line 47. Plunger 62a is pulled down to effect printing, on the sheet and platen 57, of the numeral 2. Contacts 62c now close to energize relay coil 58 in a previously described manner. Contacts 62b, in closing, energize relay coil 72 by completing a circuit as follows: from line 46, escapement contacts 58, interposer solenoid 72, contacts 62b, to line 47. Interposer solenoid 72, upon being energized, closes interposer contacts 74 to energize the punch magnet 75 by a circuit from the line 48, latch contacts 69 in the position shown, punch magnet 76, interposer contacts 74, to line 47. In the well-known manner the energization of punch magnet 75 causes the punching of the digit "2" in the record card.

Punching operation

The punching impulse is effected in the first column of the card in the punching position. A skip bar may or may not be used as desired. If no skip bar is used the card is spaced column by column to a first punching position in a manner which is explained later. Energization of the punch magnet 75 causes the depression of the usual punch motor bar on a punch which punches the record card and permits it to move forward one column ready to receive a new perforation. The forward movement of the record card places the just punched column of the card in a position under contact block 23 (Fig. 2a). At the time the record card was fed into the punch, the card rack left contacts 84 (see Fig. 2) are closed causing the energization of relay coil 58 by a circuit from the right hand side of line 47, relay coil 59, punch rack left contacts 84, to line 48. Relay coil 59 is maintained energized through its contacts 58a and last column contacts 76, both now closed. With relay coil 59 energized, contacts 59b are also closed to complete an analyzing circuit as follows: from line 47 (Fig. 2a), contacts 59b now closed, contact block 23, hole in the card which in this case represents a "2," brush 22 at the "2" position in the card, relay coil 78, to line 46. The circuit just traced ener-

gizes coil 78 causing contacts 78a to close and complete a circuit to energize a coil 88 as follows: from line 47, emitter strip 82, brushes 83, segment spot 85, contacts 78a now closed, relay coil 88, to line 46. Relay coil 88 is then maintained energized through its 88a contacts, now closed, and the normally closed contacts 95a. Closure of contacts 88b places relay coil 87 in parallel with relay coil 88 thereby to effect its energization.

Storing of the data

The next depression of a key at station "A" causes the transmission of a new series of impulses to station "B" and effects the printing of its corresponding character and the punching of the same in the record card in the manner just described. The card is allowed to escape a column after a punching operation and this shifts brushes 84 on the emitter strip to spot 86 and the brushes 22 then analyze the column that has just been punched in the record. Energization of one or more of the coils 77, 78, and 79 brings about the closure of corresponding contacts 77b, 78b, and 79b respectively to energize character relays 96, 97, and 98 respectively. Since the brushes 84 have escaped to the segment spot 86, the new closure of contacts 77a, 78a, etc. will have no effect upon the 87, 88 and 89 coils. Each new series of signal impulses, transmitted from station "A" to station "B" will thus cause the energization of an additional series of relays in the storing mechanism. For the purpose of clarity and to save space only three storing positions have been shown, though obviously one would be provided for each data-receiving column in the card.

Card spacing operation

When it is desired to space between numerals, the space key 14 (Fig. 1) at station "A" is depressed to cause the sending of four impulses to station "B" and the subsequent energization of relay R4 in the usual manner at station "B." When relay contacts 55b (Fig. 2) close, the solenoid 94 is energized by a circuit through contacts R4c in the transferred position to effect a spacing of the typewriter at station "B." Contacts 94b close to complete a circuit for energizing a space control relay 100 from line 46, relay 100, contacts 94b, to line 47. Relay 100, upon becoming energized closes its contacts 100a (Fig. 2a) to complete a circuit from the right hand side of the line 47, contacts 100a, relay 89, to line 46. Closure of contacts 89b energizes relay coil 89 in the following manner: line 47, emitter strip 81, brushes 83, segment spot 86a, relay contacts 89b, relay coil 89, to line 46. Brushes 84 which contact the emitter strip 81 are placed one column ahead of brushes 83. The purpose of this is to cause the energization of the relays in an advanced position of the relay storing unit while the space control relay 100 is energized. Relay 89, the energizing circuit for which was just described, is located in the advanced position of the storing mechanism. When relay 89 becomes energized it is held in an operated condition through its contacts 99a which close. Contacts 99b also close and provide a circuit to energize relay coil 98 as follows: from line 47, contacts 99b, relay coil 98, to line 46. Relay coil 98 is held through its contacts 88a which close, and contacts 88b close to complete a circuit to relay coil 87. Similarly, a circuit is completed to energize relay coil 88 so that each of the relays 86 to 89 now remain energized.

Relay 100 functions to cause the record card in the punch to be spaced one column by a circuit from line 46 (Fig. 2), center and upper contacts 69, punch magnet 75, contacts 100b now closed, to line 47. The energization of the punch magnet 75 causes a spacing of one column to occur even though no punching is effected. The blank column on the card which was just spaced is now positioned at the analyzing station. The column being blank, no circuits are completed through the analyzing brushes 22 to the character relays of the storing mechanism. The brushes 34 are now resting on a segment spot 86 corresponding to spot 86a which was previously occupied by brushes 83, and no circuits may be completed from spot 86 to any of the character relays because none of the contacts of the relays 77 to 79 are operated at this time, due to the fact that the analyzed column was blank. Also, before this time relay 100 has become deenergized by the energization of relay coil 53 (Fig. 2) following the closing of contacts 94c. Contacts 53a are opened to break the holding circuit to relay coil R4 and, when contacts R4c shift back to their normal position, the circuit to coil 100 is broken. The fact that relay coil 100 is deenergized prevents any circuit to the coils 80, 80, 80, etc. (Fig. 2a) because contacts 100a are open.

It has been shown in the foregoing description how impulses representative of numerical data and spaces between such data are transmitted. Likewise, the reception of these representative impulses at a distant station "B" to effect punching and printing has been explained in detail. It has also been shown how an analyzing mechanism cooperating with the punched record card column effects the set up of a relay storing mechanism to hold the data represented by the perforations for use at a later time. The method of reading out this data from the storing unit and transmitting the same back to station "A" for verification purposes is the next step in the sequence of events and will now be explained.

Card eject

When the card has been completely punched and/or spaced out to the last column position, a pair of last column contacts 76 open to deenergize relay 59. Just after the opening of contacts 76 another pair of last column contacts 110 close. The opening of contacts 76 and deenergization of relay 59 cause opening of contacts 59b and prevent further circuits through contact block 23 (Fig. 2a). The closure of contacts 110 (Fig. 2) energizes stacker magnet 105 by a circuit from line 46, contacts 110, stacker magnet 105, to line 47. Energization of stacker magnet 105 causes ejection of the just punched record card in a manner familiar in the art.

Transmission of verifying impulses from "A" to "B"

The operator at station "A" now depresses key 16 (Fig. 1) which causes transmission of six impulses from station "A" to station "B." Key 16 is known as the verification key and reception of the six impulses at station "B" energizes relay R8 in the customary manner. When contact 55b closes at station "B" (Fig. 2), a circuit is completed to energize solenoid 102 through the shifted contacts R8c and cause the closure of its contacts 102b and 102c. When contacts 102b close, relay 103 becomes energized and is held through its relay contacts 103a now closed and the normally closed contacts 85b. Closure of contacts 103b (Fig. 2a) completes a circuit as follows:

line 47, wire 107, relay coil 108, contacts 114c, relay contacts 120b in the position shown, through segment spot 24f and rotating arm 28, relay contacts 108b, to line 46. Relay 108 is held energized through its contacts 108a and cam contacts CC-4. The CC cams at station "B" operate in synchronism with arm 28. The purpose of the 114c contacts is to prevent energization of relay 108 until the commutator 115 is resting in its next transmitting position. With relay 108 energized, its contacts 108b close to complete a readout circuit. Assuming that relay 87 is energized to represent a "1" stored in the initial column, the readout circuit may be traced from line 47, relay coil 11, relay contacts 108b, contacts 120d, resistance 112, relay contacts 120c in the position shown, commutator 115 and brush 117, through the first active segment spot 115a, wire 109, contacts 87c now closed, segment 24a, arm 28, contacts 108b now closed, to the other side of the line 46. Energization of 111 by the above circuit closes its points 111a to pick up coil 113 which is then maintained energized through cam contacts CC-5.

Contacts 113b prevent shifting the commutator 115 unless readout from the storing unit has just occurred. These contacts now close to permit the shifting circuit which will be described presently. The number of impulses to be transmitted from a certain column is dependent upon the number of character relays which are energized in that column. The number of these relays which are energized is dependent upon the number of character or space impulses which were stored in this column of storing mechanism. If a space impulse was stored therein all the readout contacts of this column would be closed. The flow of current through resistance 112 impresses a potential difference on the input to transmitter 125 and provides for transmission of these impulses back to station "A."

Retransmission from "B" to "A"

Following the completion of the transmission, the arm 28 contacts segment spot 24f and a circuit is completed from one side of the line 47, via wires 107, 108 to contacts 108d now closed, magnet 121, contacts 108c now closed, contacts 113b, through segment spot 24f, through arm 28, through contacts 108b also now closed, to line 46. Energization of magnet 121 actuates its armature 121a which moves a hook 118 towards the right. When the arm 28 has passed segment spot 24f the magnet 121 is deenergized. Its armature 121 therefore returns to its normal position under action of spring 121b. The hook 118 is therefore moved to the left and rotates the ratchet wheel 119 one tooth counterclockwise. The wheel 119 rotates the shaft 122 and likewise the brushes 117 and 123 affixed to this shaft one segment position in a counterclockwise direction. The brush 117 therefore rests on segment spot 115b and transmission from the 86-88 column of relays is now effected in a manner similar to that just described.

Following the completion of transmission from all of the setup columns, the last energization of magnet 121 and rotation of shaft 122 will bring brush 123 in contact with spot 116a. A circuit is therefore completed from line 46 via wire 137 to common segment 116, brush 123, segment spot 116a, relay coil 85, wire 124, magnet 121, either contacts 108d inclosed position, or 114a, to line 47. This circuit energizes relay coil 85 which opens its contacts 85b (Fig. 2) to deenergize relay coil 103. The opening of the 103b contacts (Fig.

2a) prevents any further energization of relay coil 108 at this time. Energization of magnet 121 rotates shaft 122 counterclockwise so as to move brush 123 to segment spot 116b. The magnet 121 remains energized until cam contacts CC-4 open to drop relay 108. At that time contacts 114a are also open and there is no complete circuit through magnet 121. When armature 121a is restored to normal, contacts 114a again close and another energizing circuit for magnet 121 is then completed in the following manner: from line 46 via conductor 137 to common segment 116, brush 123, segment spot 116b, magnet 121, contacts 114a, to line 47. Magnet 121, upon becoming energized, shifts its armature 121a in a clockwise direction to move hook 118 to the right and open contacts 114a once more to deenergize the magnet 121 and again causes a one tooth advance of shaft 122. The above sequence of events occurs from the time of the location of brush 123 on spot 116c until the brush 123 is rotated to its original or home position. Energization of relay 95 also opens relay contacts 95a to deenergize the storing relays 87-90, 96-99 and 126-129.

Verification at "A"

Reception of the verification impulses at station "A" effects the pickup of the corresponding relays R1 through R4 (Fig. 1a), depending upon the signal impulses transmitted. In a manner similar to that described for station "B", energization of these relays and subsequent closure of relay contacts 55b effects printing of the proper character at station "A". The reception of four impulses energizes the space magnet 130 to effect a spacing operation. The relay 53 at station "A" is energized after printing occurs and relay contacts 53a effect the reset of the chain relay system as previously described. The operator at station "A" now compares the printed data which was originally transmitted with the printed data which has just been received. If this data verifies, the operator depresses the card feed key 15 (Fig. 1) and printing and punching for a new record are effected. If the card fails to verify, the adjust key 17 is depressed and causes a pickup of a green or red signal at station "B". The signal circuits will be explained later. Such a signal at this time indicates to the "B" operator that the card failed to verify and accordingly the just punched card is removed. Adjustment is then made in a manner to be described presently. A new series of operations then ensues for the same data and if this also fails to verify, it is understood that the machine is in need of repair.

Dash pot control adjustment

In starting up and at various times it is necessary to adjust the dash-pot controls at both of the stations to insure proper timing of certain circuits associated with the receiving chain of relays. The present transmission system requires one or more of a series of impulses to effect transmission of statistical data as already described. Each impulse of this series energizes a corresponding relay and causes deenergization of the one just preceding it. Because of this the last relay energized is representative of the transmitted signal, and no relay must become effective until the time for picking up the last relay in the group has been passed. This timing is effected by dash-pot controlled relay contacts, the adjustment for which will now be described.

These contacts at station "B" which are dash-

pot controlled must close within a period determined by the speed of rotation of the transmitting commutator at station "A". That is, the first of a series of impulses triggers off the dash-pot relay 55. The contacts controlled by this relay must not function before the time has passed when the last possible transmitting signal impulse might be received from station "A".

Therefore, since the first impulse from station "A" triggers off the dash-pot relay at B, if the time of closure of these points is checked by an additional impulse following the time of signal impulses, it is possible to determine if the adjustment is correct or not on the dash-pot relay. Means is provided to automatically effect correct adjustment at station "B" by the signal of adjustment from station "A" and likewise station "B" to "A." For the machine to be in adjustment, the contacts 55b must close following the completion of the signal impulses and while the arm 21 at station "A" is contacting segment spot 20m.

When starting up sending operations, for example, each morning prior to beginning transmission, the operator at station "A" begins the adjusting operations. Operator at station "A" depresses the adjusting key 17 and operator at "B" opens receiving switch 56 prior to adjusting to prevent printing. Depression of key 17 effects the transmission of seven impulses to station "B" and energization of relay R7 at this station in the customary manner. Sets of contacts 55c, 55d, and 55e are operated concurrently with contacts 55b for testing the adjustment, and contacts 55f concurrently with 55a. The segment spot 20m which is used for adjusting purposes is longer than any of the other segment spots. This is to hold relay R7 energized for an appreciable period and allow some tolerance in the adjustment of the dash-pot relay. Relay R7 is not provided with the usual holding circuit through contacts at station "B." Hence, relay R7 is energized only while the arm 21 contacts segment 20m. If contacts 55c close while relay R7 is energized, the dash-pot (Fig. 2) control is in adjustment, and a circuit is completed as follows: line 48, relay contacts 55c now closed, relay contacts R1e now closed, contacts 131c, coil 133, to line 47. Relay 133 upon energization is held energized through its points 133c and relay contacts 51d and 120r. Relay contacts 133a, in closing, light a green lamp in the holding circuit which informs the operator at station "B" that his machine is in adjustment. Also, relay 63 is energized to open its 63a contacts and drop relay 56. Operator at "B" would then begin sending an adjusting impulse to station "A" to operate similar circuits at the latter station in a manner to be described shortly.

If the dash-pot control at station "B" is too rapid, the sequence of events is as follows: The contacts 55e become closed before the adjusting impulse opens contacts R1g and relay coil 131 is energized by a circuit from line 48, contacts 55e, contacts R1g, relay coil 131, to line 47. Relay coil 131 is held energized through contacts 131a and contacts 51d and 120r. Contacts 131b close to energize relay coil 132 when R1h closes, coil 132 being then held through contacts 132a, 51d and 120r. Relay contacts 132a, in closing, light a red lamp in the holding circuit to show that the adjustment is not correct.

If the dash-pot control at station "B" is too slow, contacts R1f open and close before contacts 55d open and thus relay coil 134 is ener-

gized. Also, coil 131 is energized, but coil 132 is not energized at this time. A red light in the holding circuit indicates machine is still out of adjustment. The energization of coil 134 automatically effects an adjustment of the dash-pot mechanism to speed up the relay action by closing points 134b and energizing the adjusting magnet 135 (Fig. 2a) which causes shaft 6 (Fig. 6a) to rotate counterclockwise to effect a speeding up of the dash-pot action by increasing the size of the opening 7 as has been previously explained. Closure of 132b points energizes magnet 136 to slow up the dash-pot action by causing a clockwise rotation of shaft 6.

To transmit an adjusting impulse from "B" to "A" the adjust key 104 is depressed to energize relay coil 120 (Fig. 2). Relay 120 is then held through its contacts 120a and normally closed contacts 138d in parallel with CC-6. The 120e contacts (Fig. 2a), in closing, cooperate with the shifting of contacts 120b to provide a circuit for picking up relay coil 138 when arm 25 contacts spot 24j. The 138b contacts then close to provide for transmitting the adjusting impulses through the contacts 120f, g, h, k, m, and the transferred contacts 120c and d. An impulse circuit may be traced as follows: from line 47, contacts 120d in a shifted position, resistance 112, contacts 120c in a shifted position, contacts 138b now closed, contacts 120f, 120g or 120h, etc. now closed, corresponding commutator segment 24a, 24b, or 24c, etc., arm 25, contacts 120e to line 46. The last impulse occurs when arm 25 is on segment 24e and effects adjustment at "A" in a manner similar to that already described for station "B."

The operator at "A" seeing his adjusting lights flashing knows station "B" is in adjustment, and that he may discontinue transmission of his adjusting signal to station "B." Station "A" being in adjustment, the operator there sends back a single adjusting impulse to station "B" which indicates this fact to the "B" operator. The relays 131-134 are deenergized either upon the next incoming signal, at which time relay coil 51 is energized and opens its 51d points, or when contacts 120r open upon sending an adjusting signal. Relay coil 120 (Fig. 2) is held energized through contacts 138d and CC-6 in parallel. Contacts CC-6 close before coil 138 is energized to open its contacts 138d, but contacts CC-6 open before contacts 138d reclose upon deenergization of 138, and relay 120 is dropped at this time.

Relay coil 55 becomes deenergized when the solenoids 135 or 136 shift their associated ratchet arms 91 and 92 so as to open contacts 60 or 61. When the adjustment is correct, pick-up of relay coil 63 (Fig. 2) opens 63a (Fig. 2) to drop coil 55. While coil 63 is energized the holding circuit of coil 55 is open, and it is necessary therefore that coil 51, when energized, remains in its operated condition long enough to drop coil 63. Coil 51 is then deenergized in a previously described manner and its contacts 51c close to pick up coil 55 once again.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is

the intention therefore to be limited only as indicated by the scope of the following claims.

What is claimed is:

1. A data recording system comprising a first station having therein a direct recording means to record original data, data transmitting means for transmitting a series of signals representing said original data, receiving means for receiving check-back signals, and an indirect recording means for recording data represented by said check-back signals for visual comparison with the original recorded data; in combination with a second station having duplicating means controlled by the transmitted data signals for duplicating the data on a multi-column record, each column of said data being duplicated in a corresponding column of said record, analyzing means for analyzing each column of data immediately after it is duplicated, storing means controlled by the analyzing means to retain the duplicate data from the analyzed columns of the record until a predetermined later time when all of the transmitted data has been duplicated, and readout means cooperating with the storing means at said later time for sending out check-back signals representing the duplicate data to the first station.

2. A data recording system comprising a first station having therein a direct recording means to record original data, data transmitting means for transmitting a series of signals representing said original data, receiving means for receiving check-back signals, and an indirect recording means for recording data represented by said check-back signals for visual comparison with the original recorded data; in combination with a second station having duplicating means controlled by the transmitted data signals for duplicating the data on a multicolumn record, each column of said data being duplicated in a corresponding column of said record, analyzing means for analyzing each column of data immediately after it is duplicated, a plurality of groups of relays, one group for each data-receiving column of the record, selectively energized under control of the analyzing means for retaining the duplicate data from the analyzed columns of the record until a predetermined later time when all of the transmitted data has been duplicated, and readout means cooperating with the energized storing relays at said later time for sending out check-back signals representing the duplicate data to the first station.

3. A data recording system comprising a first station having therein a direct recording means to record original data, data transmitting means for transmitting a series of signals representing said original data, receiving means for receiving check-back signals, and an indirect recording means for recording data represented by said check-back signals for visual comparison with the original recorded data; in combination with a second station having a plurality of serially arranged relays adapted to be energized in succession by the transmitted data signals in accordance with the magnitude of the data represented by said signals, record perforating means controlled by the last energized relay in the series to make duplicate data perforations in predetermined columns of a multicolumn record, analyzing means effective immediately upon completion of a data perforation in a column of the record for analyzing said column for said perforation, storing means controlled by the analyzing means to retain the duplicate data from the

analyzed columns of the record until a predetermined later time when all the transmitted data has been duplicated in the form of perforations in the record, and readout means coacting with said storing means at said later time for sending check-back signals representing the duplicate data to the first station.

4. A data recording system comprising a first station having therein a direct recording means to record original data, data transmitting means for transmitting a series of signals representing said original data, receiving means for receiving check-back signals, and an indirect recording means for recording data represented by said check-back signals for visual comparison with the original recorded data; in combination with a second station including therein signal responsive means comprising a plurality of serially arranged relays adapted to be energized in succession by the transmitted data signals in accordance with the magnitude of the data represented by said signals, perforating means associated with said relays and arranged for selective control thereby, time delay means for delaying the operation of the perforating means until all of the signals representing a digit value of said data have been received by said relays so as to render only the last energized relay in the series effective to cause operation of the perforating means to make a duplicate data perforation in a predetermined column of a multicolumn record, analyzing means effective as each data perforation is made in a column of the record for analyzing said column for said perforation, a relay storing unit controlled by the analyzing means for retaining the duplicate data from the analyzed columns of the record until a predetermined later time when all the transmitted data has been duplicated in the form of perforations in the record, and readout means coacting with said storing means at said later time for sending check-back signals representing the duplicate data to the first station.

5. In combination, a primary station including therein means to transmit a series of impulses representing original data characters, original data recording means for recording said characters, and means responsive to check-back impulses for recording data characters represented by said check-back impulses for visual comparison with the original recorded data; and a remote secondary station having receiving means responsive to said impulses, record perforating means controlled by the receiving means to make character-representing perforations in successive columns of a multi-column record so as to duplicate the data character analyzing means effective upon completion of each operation of the perforating means for analyzing the column of the record for the perforation just made therein by said operation, storing means controlled by the analyzing means to retain the character values from the analyzed columns of the record until a predetermined later time when all of the character impulses have been received and the record perforated accordingly, and readout means coacting with the storing means for sending check-back impulses representing the duplicate data characters to the primary station.

6. In combination, a primary station including therein means to transmit a series of impulses representing an original data character in a predetermined time interval, original data recording means for recording said character, and means responsive to check-back signals for re-

cording the data character represented by said check-back signals for visual comparison with the original recorded character; and a remote secondary station having means for receiving said impulses during said time interval, perforating means selectively controlled by the receiving means to make a perforation representing said data character in a record, means to analyze said record for said perforation immediately upon operation of the perforating means, storing means controlled by the analyzing means for retaining the character represented by the perforation until a predetermined later time after said time interval readout means cooperating with the storing means at said later time to send check-back signals corresponding to the character perforation in the record back to the primary station.

7. In combination, a primary station including therein means to transmit a series of impulses representing an original data character in a predetermined time interval, original data recording means for recording said character, and means responsive to check-back signals for recording the data character represented by said check-back signals for visual comparison with the original recorded character; and a remote secondary station having means for receiving said impulses during said time interval, perforating means selectively controlled by the receiving means to record the character on a record, time delay means for rendering the receiving means ineffective to operate the recording means until after a time delay corresponding to the predetermined time interval, analyzing means effective immediately upon recording of the character to analyze said record for said character, means to retain the analyzed character until a predetermined time subsequent to the aforesaid time interval, and means controlled by the character retaining means for sending check-back signals representing the character as perforated in the record back to the primary station.

8. In a data recording system, a first station comprising a rotary distributor means to transmit multiple impulses representing original data during successive cycles, impulses representing one data character being transmitted in each of said cycles, original data recording means for recording the original data, receiving means responsive to check-back signals, and recording means controlled by said receiving means for recording data represented by said signals for visual comparison with the original recorded data; in combination with a second station having therein a receiving means to receive the impulses representing one data character during one of the aforesaid cycles of the distributor means, a recording means controlled by the receiving means and including means for perforating a record card to represent the data character received, time delay means for rendering the receiving means ineffective to operate the recording means until all of said data impulses representing said character are received, analyzing means operable immediately upon perforation of the card for analyzing said card for the data perforation therein, storing means controlled by the analyzing means to retain the analyzed data character until a predetermined subsequent time when all the data has been received and punched in the card, and readout means coacting with said storing means at said subsequent time to cause check-back signals rep-

resenting the data perforation to be sent to the first station.

9. A transmission system for data comprising, in combination, a first station having means to transmit multiple impulses representing said data during successive time intervals, impulses representing one digit value of said data being sent during each said interval, original data recording means for recording the original data, and data comparing means responsive to check-back signals for comparing data represented by said signals with the original recorded data; and a second station having an impulse receiving means comprising a series of digit value manifesting relays adapted to be energized in succession in accordance with the number of impulses received during one of said time intervals, perforating means for making a perforation representing a digit value in a predetermined column of a multicolored record, delay means for rendering all of the relays ineffective to operate said recording means until the end of the aforesaid time interval at which time only the last energized relay of the series becomes effective to operate the perforating means and thereby to record on the record the digit value manifested by said last energized relay, analyzing means effective immediately upon completion of an operation of the perforating means for reading the digit value from the record while other character impulses are being received in the next time interval to effect a perforation in the next column of the record, storing means for storing the analyzed digit values of data from the record until a later time when all the data has been received and punched in the record,

5 and readout means effective at said later time for reading out the stored digit values and sending check-back signals representative of said digit values back to the first station to effect operation of the data verifying means at that station.

10. A data recording system, a first station comprising a rotary distributor means to transmit multiple impulses representing digit values of original data during successive cycles, impulses representing one digit value of original data being transmitted during each said cycle, recording means to record said original data, and data comparing means responsive to check-back signals for comparing the data represented by said check-back signals with the original recorded data; in combination with a second station comprising a receiving means to receive the impulses representing a digit value during one of the aforesaid cycles of the distributor means at the first station, a recording means controlled by the receiving means and including means to perforate a record card to represent said digit value, sensing means operable immediately upon perforation of the card to sense said perforation 25 while the rotary distributor means at the first station continues in operation to send out further digit value impulses to perforate the card in a new location during the next cycle, storing means for storing the digit values as they are analyzed from the card, and readout means effective at the end of a predetermined number of cycles for reading out the stored digit values and sending check-back signals representing the latter values back to the first station to operate the data verifying means at that station.

JAMES W. BRYCE.
